UNITED STATES PATENT OFFICE.

ROBERT G. BROWN, OF SWARTHMORE, PENNSYLVANIA, AND JOHN E. STRIETELMEIER,
OF CINCINNATI, OHIO; SAID BROWN ASSIGNOR TO SAID STRIETELMEIER.

PHONOGRAPH-REPEATER.

1,322,286.

Specification of Letters Patent. Patented Nov. 18, 1919.

Application filed February 8, 1917. Serial No. 147,530.

To all whom it may concern:

Be it known that we, ROBERT G. BROWN and JOHN E. STRIETELMEIER, both citizens of the United States, and residing at Swarthmore, in the county of Delaware and State of Pennsylvania, and at Cincinnati, in the county of Hamilton and State of Ohio, respectively, have invented a new and Improved Phonograph-Repeater, of which the following specification is a full disclosure.

This invention deals with mechanisms for enabling phonograph records to be automatically re-played any desired number of times and then to stop the running of the machine; and it more especially contemplates a device in the nature of an attachment that may easily be secured to any conventional type of phonograph to impart thereto the capacities aforesaid.

20 The herein revealed construction embodies the fundamental mechanical characteristics and functional principles disclosed and claimed in the parent application of Robert G. Brown, No. 2834, filed January 18, 1915, 25 and in the division thereof No. 120,305, filed September 15, 1916, as well as the joint applications of Robert G. Brown and John E. Strietelmeier, No. 114,103, filed August 10, 1916, No. 120,302, filed September 16, 1916, 30 and No. 131,842, filed November 17, 1916.

This construction effects various structural improvements over the aforesaid arrangements, whereby (1) certain parts are eliminated; (2) the device is rendered more compact; (3) it is less costly to make; (4) it is more completely universal in its application to various types of phonographs; (5) it is easier to adjust; and (6) it is smoother in operation.

40 Other objects will be in part obvious from the annexed drawings and in part indicated in connection therewith by the following analysis of this invention.

This invention accordingly consists in the features of construction, combinations of parts, and in the unique relations of the members and in the relative proportionings and disposition thereof; all as more completely outlined herein.

50 To enable others skilled in the art so fully to comprehend the underlying features thereof that they may embody the same by the numerous modifications in structure and relation contemplated by this invention, drawings depicting a preferred form have

been annexed as a part of this disclosure, and in such drawings, like characters of reference denote corresponding parts throughout all the views of which:

Figure 1 is a plan showing the device affixed to a Victor machine. Fig. 2 is a side elevation of Fig. 1. Fig. 3 is a plan with the cover broken away to expose the interior arrangements. Fig. 4 is a side elevation with the side-walls similarly broken away. Fig. 5 shows the device provided with a modified lifting-arm adapting it to Columbia machines. Fig. 6 shows another modified lifting arm, while Fig. 7 shows still another arrangement. Fig. 8 represents the upper portion of the post.

The tone-arm lifter embodies a pendulous member Z which has also a rotary movement; the pendular motion operating to raise and lower the tone-arm, and the rotary motion serving to return it to its starting point. This member Z is conveniently in the form of a tube having its upper portion flattened to constitute a non-circular socket capable of receiving the flattened shank of an arm Y that extends into an appropriate engagement with the tone-arm of the phonograph. This member Z is located within a hollow conical post X that rises from near one corner of a sheet-metal housing W which also serves as a base. The upper end of the member Z has a fit affording free play in the upper end of the post X so as to form a universal pivot therewith, but the lower end of the member Z has a floating support whereby it may have its position shifted to give it the pendular motion which results in raising and lowering the free end of the arm Y. This floating support is constituted as follows:

Within the housing W is a suitable bracket V providing a shelf or platform provided with an elongated slot 1 through which extends the round lower end of the pendule Z so that said slot will determine its swing and confine it properly. The pendule is moved by a bar U which at predetermined periods is translated so as to pull the lower end of the pendule over to the other end of the slot 1. This is done by a mechanism adapted at intervals to be connected to derive power from the turn-table of the phonograph, as will be described. This mechanism is so constructed that, when the tone-arm reaches the end of the record groove,

said mechanism will be driven by the turn-table which will result in a translation of the bar U to cause an uplift of the tone-arm; which will be held up sufficiently long for it to be shifted to its starting point, whereupon it will then be gradually lowered.

The connection between the pendule Z and the tone-arm or stylus, as the case may be, of the phonograph is established through the agency of an arm appropriate to the style of phonograph. Fig. 1 shows a "Victor" phonograph embodying a major tone-arm T pivoted at its rear end to swing about a fixed vertical axis and having hinged (about a horizontal axis) to its forward end the minor tone-arm S which has a sound box R secured to its free end. This sound-box carries the usual stylus Q which rides in the groove of the record P that is carried by the usual motor-driven turn-table O. In this instance, we prefer to provide the sound-box with a special hook N which may be a stamping of sheet metal having a recess 3 adapted to embrace the neck of the sound-box R and having a position locating hole 4 for one of the screws of the sound-box. A hook proper 5 is formed to engage with the hook 6 of the arm Y which is formed of a rod bent as shown and having its stem 7 flattened to prevent it from turning in the socket of the pendule Z.

As shown by Fig. 5 however, the arm Y' may have its hook-like end 8 bent at an angle with the shank 9 so that it may directly support the tone-arm and slip sufficiently along the same to compensate for the lack of coincidence of the pivots of the tone-arm and lifting arm, respectively. Instead of providing for slippage in this manner, the lifting arm may have a telescopic construction, as shown by Fig. 6, or it may operate through an eye 10 in the clamping 11, as shown by Fig. 7.

The tone-arm shifter causes the tone-arm to swing from the end of the record to its initial point and this is achieved by a horizontal swing of the arm Y effected by a rotation of the pendule Z. This is done by a crank-arm M which is loosely journaled at one end to the pendule and supports its weight by means of the lip 12 projecting therefrom. The arm M is at 13 pivoted to a vibrator L and it has a resilient lost-motion connection with the pendule; this consisting of a helical spring K' fastened at one end to and coiled about the pendule and having its other end extended over the shoulder 14 of the crank-arm M so as to be put under tension during the anti-clockwise swing of said arm. This imposes a resilient or yielding turning of the pendule for the purpose of returning the tone-arm and, since this motion is impositive, it automatically compensates for variations in the setting of the stop K

which determines the initial position of the tone-arm. This stop consists of a metal strip bent to form an eye 15 and provided with a thumb-screw 16 for clamping it in any predetermined position to the post X. It has an upstanding finger adapted to act as an abutment to limit the swing of the tone-arm under the urging of the spring K'. When the crank-arm swings back, the tension in the spring is relieved and the lost motion latent in the resting of the spring on the shoulder 14 leaves the tone-arm free to travel unobstructedly in the groove of the record-disk.

The brake consists of a member J urged by a spring I against the turn-table P; said member being normally held against such movement by a controller H in the nature of a cycle-counter. This brake member J is a sheet-metal stamping having an off-set end 17 and two side wings 18 and 19; the upper of which provides abutments 20 and 21 which provide the two limits of setting of the controller H, the former 20 for continuous operation, and 21 affording a stop. The controller H is pivotally carried by the member J, and it provides a slot 22 adapted to receive a stud 23 projecting from some stationary part, such as the casing W. When the slot coincides with the stud it will be perceived that the controller H, together with the brake J, are permitted to move, thus throwing the brake into effective operation. The controller carries a pin 24 which is adapted to be brought against either the abutment 20 or the abutment 21 to determine the position of the controller. When said pin rests against abutment 21, the slot 22 coincides with the stud 23 and this corresponds with a "stop" adjustment of the device. This controller also is provided with a number of ratchet teeth 25 each of which represents one complete cycle of the machine; in other words the record may be replayed as many times as there are teeth and then automatically stopped. The controller also provides a toothless contour 26 which represents a "continuous" playing. This controller H is intermittently actuated by means of a tooth 27 projecting from the vibrator "L" which, by means of a crank pin 28, derives reciprocatory motion. The shaft 29 of the controller projects through the case W and carries an indicator 30 and a thumb-screw 31 for bringing it into registry with suitable markings on the casing W for the purpose of predetermining the operation of the mechanism. The various parts are all actuated by power derived from the turn-table of the phonograph. This is done by means of a shifttable frame G which swings about a fixed pivot 32 to which is affixed a gear-wheel 33. Pivotally carried by the frame G is a friction-wheel F which is adapted to be thrown against the periph-

ery of the turn-table so as to be rotated thereby and through a train of gears 34, 35 and 36 rotating the gear 33 to reciprocate the vibrator L. The mechanism for causing this swing of the frame G in and out will be described.

The resetting control comprehends a trip arm E which terminates in a position such that it may be hit by the tone-arm as soon as 10 it completes the playing of the record. This imparts slight movement to the arm E which ultimately results in tripping the frame G permitting it to throw the friction-wheel F against the turn-table. Within the casting is an arm D which at one end is fixed to a shaft 37 rotatably upstanding in the fixed post 38. The upper end of this shaft provides a seat for the trip lever E and a split resilient collar 39 presses the parts together sufficiently to create some little friction. The other end 40 of the arm D bears against an extension 41 from a latch C which is pivoted at 42, and near its other end provides a shoulder 43 adapted to engage the 25 part 44 of a lever B. This lever has an extension 45 from the end of which a spring 46 extends into connection with the latch C thereby tending to keep these parts engaged. This lever B is pivoted at 47 to the frame G 30 and it also has a third extension 48 which has a hook-like end adapted to ride on a cam A which is fixed to the shaft 32. As soon as the tone-arm hits the trip arm E the shoulder 43 is disengaged from the lip 44 35 and the frame G swings under the pull of spring 46 to bring the friction-wheel F against the turn-table. Thereupon, the cam A begins to rotate and this swings the lever B around until the lip 44 is again engaged 40 with the shoulder 43. During this time the tone-arm has been returned to its initial position and now the end of the extension 48 will drop down the latch 49 of the cam with the effect that the spring 46 operates to 45 swing the lever B about 43 as a fulcrum and withdraw the friction wheel F. This proc-

ess repeats as long as the brake does not stop the turn-table.

Without further analysis, the foregoing will so fully reveal the gist of this invention 50 that others can by applying current knowledge readily adapt it for various applications without omitting certain features that, from the standpoint of the prior art, fairly constitute essential characteristics of the 55 generic or specific aspects of this invention, and therefore such adaptations should and are intended to be comprehended within the meaning and range of equivalency of the following claims.

Having thus revealed this invention, we claim as new and desire to secure the following combinations of steps and elements, or equivalents thereof, by Letters Patent of the United States:

1. A phonograph repeater combining an arm pivoted to swing about an upstanding axis and connected to shift the tone-arm of a conventional phonograph; mechanism adapted to provide power for swinging said arm; a stop for said arm; and a resilient element adapted to transmit motion to said arm, whereby it may yield to compensate for the limit of movement caused by said stop.

2. A phonograph repeater combining a post adapted to be tilted and to be rotated; positive means for tilting said post; im- 70 positive means for rotating said post; and mechanism for actuating said two means.

In witness whereof, we have hereunto subscribed our names, as attested by the two subscribing witnesses.
